ROTATABLE DISPLAY RACK

Clark B. Rollins, Jr., 1415 Elm Hill Road,
Nashville, Tenn.

Filed May 28, 1964, Ser. No. 80,197

Term of patent 14 years

(Cl. D80—10)

Fig. 1

Fig. 4

FIG. 5

FIG. 1 is a front elevational view of a rotatable display rack showing my new design, the center being broken away to indicate indeterminate length;

FIG. 2 is a top plan view thereof;

FIG. 3 is an enlarged fragmentary elevational view of one corner of one shelf unit thereof;

FIG. 4 is an enlarged fragmentary elevational view of one end of one portion of the shelf unit; and

FIG. 5 is a side elevational view of the rotatable display rack disclosed in FIG. 1, the center being broken away to indicate indeterminate length.

I claim:

The ornamental design for a rotatable display rack, as shown and described.
